FISH SCALING TOOL

Lowell W. Davis, Sr., Tarpon Springs, Fla.

Filed Jan. 14, 1963, Ser. No. 73,171

Term of patent 3½ years

(Cl. D9—6)

FIG. 1 is a perspective view of a fish scaling tool showing my new design;

FIG. 2 is a side elevational view;

FIG. 3 is a top plan view;

FIG. 4 is an end elevational view; and

FIG. 5 is a sectional view taken on line 5—5 of FIG. 2; and

FIG. 6 is a fragmentary perspective view thereof.

The side not shown is substantially the same as the side shown.

I claim:

The ornamental design for a fish scaling tool, as shown and described.
